CARL E. NORIN, OF HARTFORD, CONNECTICUT, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

1,350,173.

Specification of Letters Patent. Patented Aug. 17, 1920.

Application filed December 4, 1915. Serial No. 64,948.

To all whom it may concern:

Be it known that I, CARL E. NORIN, a citizen of the United States, residing in Hartford, in the county of Hartford and 5 State of Connecticut, have invented certain new and useful Improvements in Combined Typewriting and Computing Machines, of which the following is a specification.

This invention relates to computing machines, and is herein disclosed as applied to a combined typewriting and computing machine of the Underwood-Hanson type, wherein the numeral keys of the typewriter set up the digits written by the numeral 10 keys of the typewriter in item or temporary register, and such digits are later carried in the total register or computing wheels.

It is desirable in certain types of computing to obtain a semi-automatic computation with a plurality of registers without too much mechanism. That is to say, in certain types of computing, it may be desirable at times to add and subtract simultaneously the same set of numbers. In a 25 machine of the character to which the present improvement is applied, where subtraction is carried on by the complementary method, the mechanism for doing this is not at once obvious. By the present invention, 30 however, debit and credit computations of a rather complex character can be carried out by simply combining the complementary subtracting mechanism with register dial wheels having their numbers ascending in 35 opposite directions. In this way, the two registers can have their wheels rotated always in the same direction, to add and subtract and when they are operated simultaneously, one adding while the other subtracts. This arrangement is very simply 40 controlled from a single subtraction tappet carried by the carriage.

In order to obtain the desired result of having two registers operating in the same 45 manner, but at the same time providing means whereby one may be effective as though it were subtracting in an adding operation, I have found the object desired may be attained by inverting the order of 50 digits in one of the total registers, with the result that the operative may read one register as though it was subtracting and the other register as though it was adding, although both registers are driven in precisely the same manner.

Other features and advantages will hereinafter appear.

In the accompanying drawings,

Figure 1 is a sectional side view of an Underwood-Hanson combined typewriting and computing machine as normally adding, showing only so much thereof as appears to be advantageous for the purpose of illustrating my invention as applied thereto.

Fig. 2 is a similar section of a detail, 60 taken at a point nearer the center of the machine, with the parts at subtraction position.

Fig. 3 is a plan view of the total and temporary registers and some associated 65 parts moving into subtraction.

Fig. 4 is a detail showing the relationship of the usual Hanson type register wheel to its carry-over, the numeral wheel digits being shown diagrammatically on the side 70 of the wheels.

Fig. 5 is a similar detail showing the relationship of my register wheel with its inverted order of numerals, (likewise diagrammatically shown) to its carry-over.

Fig. 6 is a rear view of the machine seen in Fig. 1.

In the usual Underwood-Hanson combined typewriting and computing machine, 80 numeral keys 1, and alphabet keys 2 depress key levers 3, so that sub-levers 4 swing the usual type-bars 5 upwardly and rearwardly against a platen 6, in the usual traveling carriage 7, with the result that types 8 print against the front side of said platen. Said carriage 7 is normally tensioned so that it tends to travel to the left under the tension of the usual spring barrel, not shown, but is held against said travel. Said carriage, however, when the alphabet 85 and numeral keys are depressed, is permitted to feed step by step by the usual escapement mechanism, which includes a pinion 9 meshing with a rack 10 on the carriage and connected to an escapement wheel 11, said escapement wheel being under the control of the usual dogs 12 and 13, said dogs being vibrated at the depression of any key in the usual manner by means of the universal bar 14 connected thereto, which 90 universal bar is operated by heels 15 on the type-bars 5. As the typewriter carriage travels along it selects computation zones in which the numeral keys of the typewriter are effective to register in a computing 95 100 105 110

mechanism the digits which are printed by the numeral keys as they are struck.

In the present disclosure the machine is provided with the usual Underwood-Hanson rack bars 16, each of said rack bars being provided with a settable pin for each of the digits from "1" to "9," and said rack bars though normally in such a position that the numbers cannot be registered on said digit pins, are moved by the typewriter carriage into such a position in the computing zone that the pins will register the digits printed in said zone. For this purpose the pins 17 are slidably mounted in the rack bars 16, but are normally out of alinement with pin-setting bars 18, said pin-setting bars being connected to the respective numeral keys of the typewriter in such a way that when any numeral key is depressed, its pin-setting bar 18 is swung downwardly from the position seen in Fig. 1, far enough to set the corresponding pin on any rack bar 16 which is holding its pins in alinement with the pin-setting bar at the moment. For the purpose of thus swinging the pin-setting bars 18, each numeral key 1 is provided with a pendant 19 which as the key descends strikes a rock arm 20 on its rock shaft 21, thereby rocking said shaft so that said shaft will carry its pin-setting bar 18 downwardly to pin-setting position by the usual linkage 22 which is operated by a rock arm 23 fast on said shaft 21.

For the purpose of enabling the typewriter carriage to move the bars 16 to carry their pins 17 into such pin-setting alinement as has been described above, the typewriter carriage is provided with denomination-selecting dogs 24. Said dogs as the carriage travels along, are caused to ride under a series of jacks 25 pivotally mounted at 26, raising the front ends of said jacks so as to depress their rear ends *seriatim*, and thereby depress the usual denominational wires 27, with the result that each wire will move its denominational rack bar 16 to pin-setting position. The connections between the wires 27 and the rack bars 16 may be of the kind shown in application No. 783,258, filed August 6, 1913 (now Patent No. 1,287,301, dated December 10, 1918), wherein any depressed wire 27 raises the front end of its lever 28 to lift its member 29 of a transposition device, with the result that said transposition member rocks a bell-crank 30 so that the upper end 31 thereof will shift its rack bar 16 slightly forwardly, thus bringing the pins 17 thereon under the pin-setting bars 18. This movement is allowed for by a slight lost motion between the parts of the pawl and ratchet 34^a which forms a one-way acting driving connection between the rack bars 16 and the adding wheels 34. After a number has been completely set up by depressing the appropriate

digit pins 17 on the appropriate rack bars 16, said number is carried into the computing or adding wheels 34 by means of a general operator which includes a cross bar 35 adapted to be actuated in any suitable manner, as by the usual handle 36, so that said cross bar will strike the ends of the pins 17, which have been depressed and carry said rack bars forwardly by the ends of the pins which project below the bottoms of the rack bars 16. The driving forward of the racks 16 in this manner rotates the adding wheels 34 each to an extent dependent on the pin depressed on its associated rack bar. On the return stroke of the handle 36, the cross bar 35 is returned to normal position, carrying back the racks 16 to their normal position by means of lugs 36^a. The adding wheels 34 are not turned during this return movement, because of pawl-and-ratchet connections 34^a, Figs. 4 and 5, between them and the rack bars 16.

In order to rapidly position the carriage of the typewriter in an adding zone, the mechanism is provided with the usual denominational tabulating keys 37, which are pivoted between their ends, so that when depressed any one will raise to effective position its tabulating plunger 38 into the path of the usual column stop 39 adjustable along the usual rack bar 40 of the typewriter carriage. When any one of the keys 37 is depressed, it is adapted to release the typewriter carriage from the escapement wheel by mechanism of the usual kind, not shown herein, with the result that the carriage will travel freely and rapidly along until it is arrested when a column stop 39 thereon strikes the lifted plunger or counter-stop 38.

While the mechanism has hitherto been described as adapted for addition, it is also adapted to be used for subtraction, and for this purpose one or more of the column stops 39 are provided with a subtraction lug 41 extending over the computing zone, said lug being adapted to strike a subtraction controlling dog 42 as the typewriter carriage enters the computing zone, with the result that said dog will set the mechanism to subtracting position, as shown in application No. 797,714, filed October 28, 1913 (now Patent No. 1,280,065, dated September 24, 1918).

The present machine includes two registers or groups of computing wheels 34, and may include more of said registers, and where a machine includes a plurality of registers, it is usually very advantageous mechanically to provide the connections in such a way that where one register subtracts, all others subtract, or else are neutral, thus avoiding some complexities which result from building a machine which is adapted to simultaneously add and subtract.

According to the present disclosure, all the registers are set at subtracting position simultaneously, and if it is desired that one register shall appear to subtract while another appears to add, the computing wheels 34 themselves may be constructed to obtain such a result.

The mechanism now to be described may be universal for all the registers, with the result that when any register subtracts all subtract, unless neutrality has been obtained for any register, as by swinging its dog 24 to ineffective position around the usual bar 43 on which it is pivoted. To accomplish subtraction, therefore, the machine may be provided with the single subtraction dog 42 pivoted on the usual lever 44 so as to draw upwardly on the usual link 45 in the manner disclosed in the co-pending application of John N. Thornton, No. 769,132, filed May 22, 1913 (now Patent No. 1,283,360, dated October 29, 1918). The link 45 is pivoted at its lower end to an arm 46 forming part of a bail 47, with the result that whenever the dog 42 is struck by a subtraction lug 41, the link 45 is drawn upwardly and causes the bail 47 to draw a holding bar 48 from its normally effective position, in which the usual subtraction controlling arm 49 overlies it, thus permitting said subtraction arm to swing downwardly and carry to ineffective position a hook 50 fast on the shaft 51 on which said subtraction bar 49 is also fast. This releasing of the hook 50 permits a spring 52 to draw rearwardly the main subtraction bar 53 and set the machine for subtraction in the manner disclosed in said application No. 769,132.

Said subtraction setting involves a good many minor operations, since the present machine is of a complementary subtraction type, in which type of machine the adding wheels 34 are always turned in one direction as if they were adding, while subtraction is effected by setting pins which will cause the wheels to add a number complementary to that written by the types, printing at the moment.

The subtraction setting operation includes the manipulation of the usual devices for setting the "9" pins 17, said means including the usual bar 53 operated by the usual hook 54 connected to the said subtraction bar 53. In addition to setting the "9" pins, the subtraction bar when actuated shifts all the rock shafts 21 forwardly, so that each rock shaft instead of operating its pin-setting linkage 22 by its addition rock arm 23 and addition wrist 55, operates a complementary linkage 22 by means of a subtraction rock arm 57 which is effective on the linkage 22 by its subtraction wrist 56, this being done in the manner set forth in said application No. 769,132. This is effected by sliding said rock shafts 21, by means of the

usual plate 58, through the usual rock shaft 59 extending transversely of the machine.

Besides making the above connections effective, the subtraction bar 53 makes connections for restoring any "9" pin whenever any other digit pin on its own rack bar is set. For this purpose there is provided a "9" pin restoring bar 60 which is operated by the depression of any numeral key whenever any pin-setting linkage 18 is actuated in the subtraction operation. To obtain this result the rock shafts 21 are prolonged in the usual manner beyond the frame bar 61, and have fast to their ends the usual rock arms 62 which are effective to actuate in one direction only a linkage 63 connected to operate the "9" pin-restoring bar 60. All these connections may be identical with the application of Thornton No. 769,132, referred to above, and the restoring bar 60 is effective on the rear ends of the usual levers 64 connected to the "9" pins 17.

The subtraction bar and associated parts are restored to normal adding position in the usual manner by the actuation of the general operator, the parts for doing this including, among others, the usual lug 65 on the subtraction bar 53 which is adapted to be struck by the cross bar 35 of the general operator at the end of a subtraction operation. At such restoring operation the holding bar 48 is restored to its normal effective position by the usual spring 66.

In order to permit this, the mechanism is provided with the usual restoring arm 69 fast to the shaft 51 and adapted to again put the arm 49 under the control of the holding bar 48. At the end of any adding or subtracting operation the pins 17 are restored to their normal positions by the usual pin-restoring plate 70, which is actuated as usual by the general operator.

At the beginning of the subtraction operation, in addition to setting the "9" pins, the bar 53 is adapted to set a lug 67 into the path of the general operator cross bar 35, in such a way that said lug will be intercepted by said general operator and cause an extension 68 of said lug (Fig. 3) to lie behind the depressed pin on the units pin bar, thus causing said general operator cross bar 35 to drive said units pin bar one step further than it would under other circumstances. This provides for the adding of the necessary extra unit to correct the ordinary units error of complementary subtraction. The connections and utility for doing this are more fully explained in the co-pending application of William L. Gumprecht, No. 778,451, filed July 11, 1913 (now Patent No. 1,285,134, dated November 19, 1918).

While much of the above description is directed to a single item register or set of pins 17 and rack bars 16, the machine as shown herein includes two identical registers under 130

the control of the same subtraction lug 41; that is to say, both registers are set for subtraction when either of them is so set.

The machine herein illustrated is especially adapted to be used in banking accounting, in which it is desired to keep accounts of two columns of figures, one being the daily balance and the other the withdrawals. In the machine as herein illustrated, computation mechanism is provided for said two columns only, but computing registers for the remaining columns, such as deposits, etc., may be included in the machine if desired. As pointed out above, it is extremely desirable from the mechanical point of view, to have all registers which are in use at any given moment add when any add, and subtract when any subtract. On the other hand, if a register showing withdrawals is to read correctly, it must at the same time be adding when the register showing the daily balance is substrating.

To obtain a result showing addition on the withdrawal register while subtraction is shown on the balance register, I have found it possible to arrange the connections so that both registers are always doing mechanically the same operation, while, on the other hand, to the operative, the wheels of one register will appear to be adding while the wheels of the other register appear to be subtracting. To do this, I utilize the ordinary Underwood-Hanson computing wheels for my balance register in which the wheels have their numbers run downwardly, as viewed by the operative, so that when the wheels are turned by the forward driving of the racks beneath them, the fronts of the wheels move upwardly and effect adding.

For the withdrawal register I provide adding wheels 80 which are similar to the balance register wheels, but on which the numbers run upwardly, as viewed by the operative, with the result that when said wheels are turned by the forward driving of the rack bars, they will appear to subtract in an adding operation.

The machine may further be provided with the usual carry-over mechanism which in many respects is substantially identical with that shown in the applications referred to above, and in the Hanson Patent 816,319.

In the usual Underwood-Hanson machine, the carry-over tooth 72 is placed between the digits "6" and "7" so that when the adding wheel 34 is turning its dial face to carry "9" away from the sight opening 71, and "0" to the sight opening, the carry-over tooth 72 will be effective to move the carry-over wheel 73 in the usual manner by one of the teeth 76 thereon, so that on the return stroke of the general operator the usual carry-over drive shaft 74 will be effective to turn the carry-over wheels 75 *seriatim* in the usual manner by means of the usual teeth 76. This

action takes place only on the return stroke of the general operator because of the usual one-way clutch between said carry-over drive shaft 74 and the pinion 77 which drives it, said pinion being driven by a rack 78 forming part of the general operator and driving the pinion 77 by means of an intermediate idler pinion 79. In my new register the carry-over teeth 72 are placed between the digits "2" and "3," on the numeral wheels 80 which form the adding wheels in said register. Since the group of adding wheels 80 turn in the same direction as the group of adding wheels 34, no further change needs to be made, either in the pawl-and-ratchet connections 34^a or in the carry-over wheels 75. This fact greatly simplifies, from a commercial point of view, the construction of a register such as I have described, partly for the reasons that the addition and subtraction wrists always operate all the pin-setting bars 18 identically for each register, and that the carry-over shafts may be universal to both registers, and the carry-over wheels may be identical.

In order that computation may take place in both registers simultaneously, there are provided two dogs 24, and two sets of wires 27, and jacks 25, viz., one for each of the registers shown in plan view in Fig. 3. The two dogs 24 are so adjusted along the bar 43 on which they are pivoted, that they will be held by the usual rack 81 in such position with reference to the sets of jacks 25 that both dogs 24 engage jacks of identical denomination simultaneously. While the dogs 24 have been described as being in effective position, they usually stand in ineffective position, and are only moved into effective position when computing is to be done. For this purpose there are provided the usual silencing rolls 82, each supported on its own rock shaft 83, by rock arms 84 fast on said shafts, on which arms the rolls 82 are journaled. The shafts 83 are usually held so as to keep their rolls 82 in effective position, and for this purpose each shaft 83 is provided with a coil spring 85 fast to said shaft and bearing against a bracket in which the shaft is journaled.

In the present machine there are two shafts 83 journaled in a boss 86 forming an extension of the usual denominational tabulator frame, at which boss the ends of the shafts abut against each other. Each one of the shafts 83 may be separately moved to ineffective position by swinging its roll outwardly to a point in which it will no longer support any dog 24. For this purpose each rock shaft 83 is provided with a rock arm 87 fast thereon, and lying above a manually operable tappet 88. Each tappet forms one end of a bell-crank 89 journaled at 90 and having an extension 91 extending downwardly to the bottom of the

machine where the extension is fast to a forwardly extending link 92. This link is adapted to be manually operated by its handle 93 projecting through the side of the machine where it is conveniently operated, the connections being such that when the handle 93 is pushed rearwardly, the silencing roll 82 is thrown to ineffective position where it can not support any dog 24 in the zone which that roll controls. Each roll 82 covers the same number of letter-spaces as is covered by the jacks 25, for which it is calculated to hold a dog 24 effective.

Each handle 93 is normally held in its forward position shown in Fig. 1 by means of a spring 94 which encircles the stud 90 on which its bell-crank 89 is pivoted, said spring throwing the lower arm of said bell-crank forward. Each handle 93 is adapted to be latched in its rearward position in order that the dogs 24 may be made permanently ineffective at the option of the operator. For this purpose each handle 93 extends through a slot 95 in the side of the machine, said slot being provided with a downward extension 96 adapted to catch its handle 93 and hold it when said handle is pushed rearwardly.

For the purpose of illustrating the operation of the mechanism of the new register, the following example of the steps is given:

Suppose wheels, A, B, C, D, represent thousands, hundreds, tens and units.

A, B, C, D,
If they read----- 0, 3, 6, 6,
And there is printed----- 0, 4, 2, 7,
This sets up pins for----- 9, 5, 7, 3,
(including the extra unit)
The general operator turns to----- 1, 8, 9, 3,
The carry-over makes it----- 0, 7, 9, 3,

An inspection of the above example will show that when driven by the general operator each wheel is turned to such an extent that the reading shown at the end of the forward stroke of the general operator is the reading that said wheel would have if the adding were done in an ordinary machine and a carry-over had taken place. On the return stroke of the general operator, the mechanical carry-over operation takes place, and this mechanical carry-over corrects the showing on certain numeral wheels, making the digit thereon displayed at the sight opening the correct digit for the computation in hand. In other words, the superficial examination and reading of the dial wheels appears to inform the operative that the wheels are always turned by the rack bars as if a carry-over were necessary to complete the computation, and that where no such carry-over is necessary the mechanical parts known as the carry-over mechanism erase this apparent carry-over.

Variations may be resorted to within the

scope of the invention, and portions of the improvements may be used without others.

Having thus described my invention, I claim.

1. In a combined typewriting and computing machine, the combination with numeral keys, of two item registers, each comprising a set of indexing devices settable by any of said keys, a carriage for selecting the denominations, a general operator, two total registers into which the numbers set up on the indexing devices are carried by said general operator, each total register being controlled by its associated item register, and means for simultaneously setting both item registers to subtraction condition, each of said registers comprising number-bearing dials, the numbers on the dials in one register running reversely with relation to the numbers on the dials in the other register. 70

2. In a combined typewriting and computing machine, the combination with two total registers, of two item registers, and means, whereby when both total registers 90 are driven by said item registers in the same direction, one is effective to add, and the other is effective to subtract.

3. In a combined typewriting and computing machine, the combination with typewriter numeral keys, two item registers, each including a set of indexing devices, any of which may be operated by said keys, a carriage for selecting the denominations, and a total register for each item register, 100 each total register comprising numbered computing elements, of means for modifying the connections between said keys and said item registers, so that both subtract when either subtracts, and both add when either adds, and connections so related to the order of the numbering of said computing elements that, when said total registers are operated by said general operator under the control of their respective item registers, 110 one total register will add and the other subtract.

4. In a combined typewriting and computing machine, the combination with typewriter numeral keys, of two complementary subtraction devices operated by said keys, and means, whereby one of said complementary subtraction devices is always effective to show an addition result when the other is effective to show a subtraction result. 115

5. In a combined typewriting and computing machine, the combination with numeral keys, of two item registers, each comprising a set of indexing devices settable by any of said keys, a carriage for selecting the denominations, a general operator, two total registers comprising numbered computing elements into which the numbers set up on the indexing devices are car- 125

130

ried by said general operator, each total register being controlled by its associated item register, means for simultaneously setting both item registers to subtraction condition, and connections so related to the order of the numbering of said computing elements that, when said item registers are set to subtraction condition, one of the total registers controlled thereby will subtract and the other will add.

6. In a combined typewriting and computing machine, the combination with two total registers, of two item registers, means whereby when both total registers are driven by said item register in the same direction, one is effective to add, and the other is effective to subtract; a traveling typewriter carriage for selecting the denominations in said registers, and means whereby said carriage may be ineffective to select the denominations in either register.

7. In a combined typewriting and computing machine, the combination with typewriter numeral keys and two item registers operated by said keys, of a total register for each item register, means for modifying the connections between said keys and said item registers, so that both subtract when either subtracts, and both add when either adds, connections whereby, when said item registers drive their total registers, one total register will add and the other subtract, a traveling typewriter carriage for selecting the denominations in said registers, and means whereby said carriage may be ineffective to select the denominations in either register.

8. In a combined typewriting and computing machine, the combination with two registers, having their wheels turning in the same direction, of means whereby one register turns its wheels for addition while the other turns its wheels for subtraction, a general operator for driving said registers simultaneously on one movement thereof, carry-over devices set by said registers on the same movement, and universal means for identically driving said carry-over device on the return stroke of said operator to effect subtraction in one register and addition in the other.

9. In a combined typewriting and computing machine, the combination with two registers, having their wheels turning in the same direction, of means whereby one register turns its wheels for addition while the other turns its wheels for subtraction, a general operator for driving said registers simultaneously on one movement thereof, carry-over devices set by said registers on the same movement, universal means for identically driving said carry-over device on the return stroke of said operator to effect subtraction in one register and addi-

tion in the other, a traveling typewriter carriage for selecting the denominations in said registers, and means whereby said carriage may be ineffective to select the denominations in either register.

10. In a computing machine, the combination with dial wheels having carry-over teeth placed in a definite relation to the numbers on the dials of the wheels, of a set of carry-over devices for said wheels, of a second set of dial wheels having carry-over teeth differently located, carry-over wheels for said second set of dial wheels journaled on a shaft universal to the two sets of carry-over wheels, said carry-over wheels adapted to be set by said carry-over teeth, and carry-over drive devices, effective *seriatim* on said carry-over wheels after all the carry-over wheels have been set by their respective carry-over teeth.

11. In a combined typewriting and computing machine, the combination with a typewriter carriage, and two total registers adapted to simultaneously add and subtract, of a general operator for driving said registers, said registers each comprising wheels always turned in the same direction by said operator, pin bars for so driving said registers, and tabulating stops for automatically determining when said registers shall be effective in a given manner.

12. In a computing machine, the combination with dial wheels having carry-over teeth placed in a definite relation to the numbers on the dials of the wheels, of a set of carry-over devices for said wheels, of a second set of dial wheels having carry-over teeth differently located, carry-over wheels for said second set of dial wheels journaled on a shaft universal to the two sets of carry-over wheels, said carry-over wheels adapted to be set by said carry-over teeth, carry-over drive devices effective *seriatim* on said carry-over wheels after all the carry-over wheels have been set by their respective carry-over teeth, and means whereby either register can have its connection to the carriage silenced individually.

13. In a combined typewriting and computing machine, the combination with a single set of pin-setting bars, of two sets of register wheels having numbers thereon running in opposite directions, and a separate set of pins for each register.

14. In a combined typewriting and computing machine, the combination with typewriter numeral keys and a single set of pin-setting bars operated thereby, of two registers under the control of said pin-setting bars, means for altering the connections between said keys and said bars, and two registers having dial numbers running in opposite directions adapted to compute the numbers set up by said pin-setting bars.

15. The combination with a complementary subtraction device, of two registers driven thereby simultaneously, one effective to add and the other effective to subtract.
- 5 16. The combination with two registers adapted to compute totals, of an item register for each of said total registers, means whereby each item register drives its total register always in the same direction, pin bars for so
10 driving said registers, said pin bars forming
- said item registers, connections whereby one of said total registers may be effective to subtract, a traveling carriage, tabulating stops for positioning said carriage, and lugs on certain of said stops for automatically 15 causing said subtraction on one register.
